UNITED STATES PATENT OFFICE.

GEORGE T. BRYAN, OF KANSAS CITY, MISSOURI.

WASHING MACHINE.

Application filed April 2, 1923. Serial No. 629,365.

To all whom it may concern:

Be it known that I, GEORGE T. BRYAN, a citizen of the United States, residing at Kansas City, in the county of Jackson and 5 State of Missouri, have invented certain new and useful Improvements in Washing Machines, of which the following is a specification.

My invention relates to a machine for 10 washing and wringing clothes, sheets, etc., and one object is to provide an efficient machine of this character in which clothes, etc., may be thoroughly washed and wrung without removing them from the machine, 15 thereby saving the time and labor now required when the washing is done in one machine and the wringing in another.

In carrying out the invention I employ 20 a perforated drum revolvably mounted in a cylindrical casing which is adjusted to one position for the washing operation and another position for the wringing operation, a novel arrangement of gearing being employed to drive the perforated drum with 25 an alternating rotary motion during the washing operation and with a continuous rotary motion during the wringing operation, as will hereinafter appear, reference being had to the accompanying drawing in 30 which:

Fig. 1 is a vertical sectional view of the machine on line I—I of Fig. 2.

Fig. 2 is a broken end elevation of the machine.

35 Figs. 3 and 4 are details of bearings employed in carrying out the invention.

In carrying out the invention, I employ 40 a cylindrical casing 2 provided at one end with a lid 4, which is normally held in a closed position by a suitable fastener 6. The casing 2 is provided intermediate its ends with two diametrically-opposed fixedly-mounted trunnions 8 journaled in the upper portions of a pair of standards 10 fixed 45 upon a base 12.

14 designates a perforated drum arranged concentrically within the casing 2 and nearer one end thereof than the other to leave a relatively large space 16 for a purpose which will hereinafter appear. The drum 14 is provided at one end with a lid 18, which is normally held in closed position by a suitable fastener 20.

50 The perforated drum 14 is mounted at one end upon a stub shaft 22 and at its opposite end upon a drive shaft 24 journaled

in bearings 26 and 28, respectively, fixed to opposite ends of the casing 2. The drive shaft 24 is provided at its outer end with a bevel gear 27 and a small gear 29, said gears being fixedly mounted upon said shaft. 60

When the casing 2 and the drum 14 are in the washing position disclosed by full lines, Fig. 1, the gear 29 intermeshes with a segmental gear 30 fixedly mounted upon a stub 65 shaft 32 journaled in the upper end of a standard 34 mounted upon the base 12. The stub shaft 32 is driven from an electric or other suitable motor 34^a through a train consisting of a worm 36, a worm wheel 38, a 70 bevel gear 40 fixed to the worm wheel 38, a bevel gear 42 intermeshing with the bevel gear 40 and fixedly mounted upon a shaft 44, a disk 46 mounted upon the shaft 44, a connecting rod 48 connected at its lower 75 end to the disk 46 through a wrist pin 50, and a crank 52 pivotally connected to the upper end of the connecting rod 48 and fixed upon the shaft 32. The worm 36 is loosely mounted upon the motor shaft 54 80 and has an integral clutch member 56 for engagement by a companion clutch member 58 slidably mounted upon the motor shaft 54 and having a groove-and-feather connection 59 therewith, so that it will rotate with said shaft 54. A lever 62 is provided for shifting the clutch member 58 into and out of gear with the clutch member 56. 85

The outer end of the drive shaft 24 is 90 held in proper position to hold the gear 29 in mesh with the segmental gear 30, by means of a fixed bearing member 64 and a movable bearing member 66 mounted on a pivot 68 carried by the standard 34 and provided with a hand lever 70, whereby it may be thrown to active or inactive position. The lever 70 is held in either of its positions by a notched segment 72 fixed to the standard 34. 95

When the clutch member 58 is thrown into engagement with the clutch member 56, continuous rotary motion is imparted by the motor 34^a to the disk 46 through the intervening mechanism, while an alternating rotary motion is imparted to the drum 14 through the intermediary of the connecting rod 48 and intervening gearing. 105

After the clothes or other articles within the drum 14 have been thoroughly washed 110 they may be wrung by adjusting the casing 2 and the drum 14 to the vertical position

2
disclosed by dotted lines, Fig. 1. When in the last-mentioned position all of the water drains from the drum 14 into the space 16 where it is prevented from leaking out 5 around the shaft 24 by the long bearing 28. When in the vertical position as stated, the drum 14 is driven continuously in one direction at relatively high speed to extract the water from the clothes or other articles by 10 centrifugal force. Driving of the drum 14 is effected by the bevel gear 27, a bevel gear 74, a cog wheel 76, and a pinion 78 mounted upon the motor shaft 54. The cog wheel 76 is fixedly mounted upon a counter- 15 shaft 80 journaled in bearings 82 fixed upon the base 12.

The bevel gear 74 has a groove-and-feather connection 75 with the shaft 80 and is held in frictional engagement with the 20 gear 27 by a spring 86. A stop 87 is fixed to the counter-shaft 80 to prevent the spring 86 from pushing the bevel gear 74 too far to the left. The gear 27 is held in engagement with the gear 74 by means of a fixed 25 bearing 88 and a movable bearing 90, which latter is mounted upon a pivot 92 and controlled by a handle 94 adapted to be held in either of its positions by a notched segment 96.

30 From the foregoing description it is apparent that I have provided a machine in which the gear 29 is reliably held in engagement with the segmental gear 80 during the washing operation, and the bevel gear 27 is held in engagement with the gear 74 during 35 the wringing operation; and while I have shown and described the preferred construction, combination and arrangement of parts,

I reserve the right to make such changes as properly fall within the spirit and scope of 40 the claim.

Having thus described my invention, what I claim and desire to secure by Letters Patent, is:

In a machine of the character described, 45 a cylindrical casing, trunnions fixed to said casing, supports in which said trunnions are mounted so that the casing may be rocked to vertical and horizontal positions, a perforated drum mounted in and rockable 50 with the casing, said drum being proportioned to leave a relatively large space between its bottom and the bottom of the casing when in vertical position, a shaft fixed to said drum and extending through 55 one end of the casing, a gear wheel fixed to said shaft, a segmental gear for imparting an alternate rotary motion to said gear wheel, a standard having a fixed bearing member constituting a stop for the shaft 60 when adjusted to a horizontal position to engage the gear wheel with said segmental gear, a movable bearing member for holding the shaft in engagement with said fixed bearing member, mechanism for driving the 65 segmental gear, and gearing coacting with a portion of said mechanism for driving the shaft in one direction when adjusted to vertical position.

In testimony whereof I affix my signature 70 in the presence of two witnesses.

GEORGE T. BRYAN.
